UNITED STATES PATENT OFFICE

163,342

FRUIT JUICE SHAKER

Walter J. Wagner, Wyckoff, N. J.

Application October 14, 1949, Serial No. 5,485

Term of patent 14 years

(Cl. D2—3)

To all whom it may concern:

Be it known that I, Walter J. Wagner, a citizen of the United States, residing in Wyckoff, State of New Jersey, have invented a new, original, and ornamental Design for a Fruit Juice Shaker, of which the following is a specification, reference being had to the accompanying drawing, forming a part hereof.

Fig. 1 is a top plan view of a fruit juice shaker embodying my new design; and

Fig. 2 is a side elevational view thereof.

I claim:

The ornamental design for a fruit juice shaker, as shown.

WALTER J. WAGNER.
